UNITED STATES PATENT OFFICE.

OSCAR W. MEYROWITZ, OF NEW ROCHELLE, NEW YORK, ASSIGNOR TO THE MEYROWITZ MANUFACTURING CO., OF NEW JERSEY.

DESIGN FOR A STRAP FOR EYEGLASSES.

SPECIFICATION forming part of Design No. 34,362, dated April 16, 1901.

Application filed January 4, 1901. Serial No. 42,134. Term of patent 7 years.

To all whom it may concern:

Be it known that I, OSCAR W. MEYROWITZ, a citizen of the United States, residing at New Rochelle, in the county of Westchester and State of New York, have invented a certain new and original Design for Straps for Eyeglasses, of which the following is a full, clear, and exact description.

My new and original design is for the strap or clip commonly used for mounting the lenses of eyeglasses and spectacles.

The design is illustrated in the accompanying drawings, in which—

Figure 1 is a front view of a fixture, including a post and one arm of a strap. Fig. 2 is a side view of the same, showing the features of my design; and Fig. 3 is a section through the strap, taken on line $x-x$ of Fig. 2, and also illustrating the features of my design.

The leading or material feature of my design consists of the strap or fork whose two ends are indicated by a and b , respectively, the opposing or adjacent faces of the two arms being substantially parallel and smooth throughout their length and one of said arms

appearing thicker than the other when viewed from the side, the said appearance of thickness being due to an enlargement on the side of the said arm remote from the other arm, as shown in Figs. 2 and 3. In each of the ends a and b of the strap there is a circular opening c and d , respectively. In the thicker end of the strap the opening is cylindrical and lined or surrounded by a spiral rib, giving the appearance of a screw-thread.

It is apparent that this design is applicable to any of the fixtures used on eyeglasses and spectacles for securing the edge of the lens.

I claim as my invention—

The design for a strap for the lenses of eyeglasses and spectacles herein described and illustrated.

In witness whereof I subscribe my signature in presence of two witnesses.

OSCAR W. MEYROWITZ.
